(57) **CLAIM**

The ornamental design for an objective lens, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a left side elevation view of a first embodiment of an objective lens showing our new design;

FIG. 2 is a bottom plan view thereof;

FIG. 3 is a front elevation view thereof;

FIG. 4 is a rear elevation view thereof;

FIG. 5 is a right side elevation view thereof;

FIG. 6 is a top plan view thereof;

FIG. 7 is a top and right side perspective view thereof;

FIG. 8 is a left side elevation view of a second embodiment of an objective lens showing our new design;

FIG. 9 is a bottom plan view thereof;

FIG. 10 is a front elevation view thereof;

FIG. 11 is a rear elevation view thereof;

FIG. 12 is a right side elevation view thereof;

FIG. 13 is a top plan view thereof; and,

FIG. 14 is a top and right side perspective view thereof.

The broken lines and the faded areas depict portions of the objective lens in which the design is embodied that form no part of the claimed design.
